Patented Apr. 18, 1916.

UNITED STATES PATENT OFFICE.

GUY L. BONHAM, OF WEST HARTFORD, CONNECTICUT.

SPRING-MOTOR.

1,179,604.

Specification of Letters Patent.

Patented Apr. 18, 1916.

Application filed December 7, 1914. Serial No. 875,896.

To all whom it may concern:

Be it known that I, GUY L. BONHAM, a citizen of the United States, residing at West Hartford, in the county of Hartford and State of Connecticut, have invented a new and useful Spring-Motor, of which the following is a specification.

The device forming the subject matter of this application is a spring motor and one object of the present invention is to provide novel means for connecting the actuating spring operatively with the drive shaft.

Another object of the invention is to improve the construction of the drive shaft, its mounting and coöperating parts.

It is within the scope of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing:—Figure 1 is a longitudinal section wherein sundry parts appear in elevation; Fig. 2 is a transverse section showing the winding button and attendant parts; Fig. 3 is an elevation of one of the shafts, parts being broken away and sectioned; Fig. 4 is a section detail illustrating the clutch lever; Fig. 5 is an elevation disclosing the auxiliary winding crank; Fig. 6 is a longitudinal section showing a modified form of the invention.

The invention comprises a casing including a tubular body 89 having a reduced neck 90 merging into a transverse, disk-like head 91. Threaded as shown at 92 onto the head 91 is a forward cap 93. A rear cap 94 is threaded as shown at 95 onto the tubular body 89.

The invention includes a drive shaft 96 journaled in a bearing disk 97 located at the rear end of the neck 90, the drive shaft being journaled in the head 91. Longitudinal shifting movement of the drive shaft 96 is prevented through the medium of a collar and set screw 98 which coöperate with the

bearing disk 97. Noting Fig. 3 it will be observed that in the rear end of the drive shaft 96 there is formed a recess 99 receiving for rotation the reduced forward end 100 of a winding shaft 101, the rear end of which is squared as shown at 102. Threaded into the squared end 102 of the winding shaft 101 is shown at 103 is a short stub-shaft 104 having an enlarged terminal head 105. A winding button 106 is journaled on the shaft 104 and is provided with a recess 107 which receives the head 105, the head 105 constituting means for holding the winding button 106 on the stub-shaft 104. The winding button 106 is provided with a flange 107 to which is secured a pawl 108 coacting with a ratchet wheel 109 mounted on the squared portion 102 of the winding shaft 101. Mounted on the squared portion 102 of the winding shaft 101 and located within the rear cap 94 is a ratchet wheel 110, engageable by a back stop pawl 111 secured to the cap 94.

A main beveled gear wheel 112 is journaled on the shaft 101 adjacent the forward end of the tubular body 89 and is held in place against transverse sliding movement by means of collars 114 on the shaft 101, the collars preferably being held in place by set screws. A helical spring 115 of any desired construction is located within the tubular body 89. One end of the spring 115 is attached to the main beveled gear wheel 112 and the other end of the spring is attached to the ratchet wheel 110 or to the shaft 101 as may be found expedient. A beveled pinion 116 is secured to the rear end of the drive shaft 96 and is located adjacent the main beveled gear wheel 112. A stud 117 projects inwardly from the neck 90. At this point it is to be observed that the neck 90 may have a threaded connection with the body 89 as shown at 90a in order to permit the setting up of the gear and clutch mechanisms to be described hereinafter. Held on the stud 117 is a beveled pinion 118, the hub of which is indicated at 119.

Fulcrumed as shown at 120 upon the body 89 is a lever 121 provided at its ends with buttons 122. Projecting from the lever 121 intermediate its ends is a finger 124 adapted to be engaged by either one of a pair of notches 125 formed in a spring tongue 126 struck from the tubular body 89. The lever

121 includes a depending arm 123 coacting with the hub 119 of the beveled pinion 118 to effect a shifting of the latter. The inner end of the lever 121 is provided with a lug 136 adapted to coact with a notch or opening 137 formed in the periphery of the main beveled gear wheel 112.

Secured to the forward end of the drive shaft 96 is a gear wheel 127 meshing into a pinion 128 formed upon or connected with the tubular bearing 129 of a blade holding head 130, the head 130 being of any desired form. The blade holding head permits the spring motor forming the subject matter of this application to be used in connection with a revolving safety razor. One end plate 6 of the head 130 is denoted by the numeral 133 and is provided with a boss 134 which coacts with the end wall of the forward cap 93 to hold the bearing 129 in place on the shaft 131 for rotation.

In Fig. 6 of the drawings, a slight modification of the invention is shown. In Fig. 6, parts hereinbefore alluded to are denoted by the reference characters previously used, with the suffix "a". In this modification, the actuating spring 200 is of helical form but comprises a plurality of nested, conical convolutions. Owing to the construction of the spring 200, the same may consist of a maximum number of convolutions or coils for a given length of the spring measured along its axis. The spring, therefore, will possess great resiliency and strength in a compact form.

In practical operation, the lever 121 is tilted into the position shown in Fig. 1, the finger 124 being engaged with one of the notches 125 in the spring tongue 126. Under the circumstances above pointed out, the lug 136 on the lever 121 will be engaged in the notch or recess 137 in the main beveled gear wheel 112 and thus the latter will be prevented from rotating on the shaft 101. Since one end of the spring 115 is connected with the main beveled gear wheel 112, that end of the spring will be held.

A rotating, oscillating motion may be imparted to the winding button 106 and the latter through the medium of the pawl 108 and the ratchet wheel 109 will impart motion to the winding shaft 101 and to the ratchet wheel 110 and thus the spring 115 will be put under tension, the back stop pawl 111 coöperating with the ratchet wheel 110 to maintain the tension thus secured.

When it is desired to impart rotary motion to the drive shaft 96, the lever 121 is tilted to withdraw the lug 136 from the notch 137 in the main gear wheel 112 and by this same operation, the beveled pinion 118 will be shifted to the left, referring to Fig. 1; due to the action of the arm 123 of the lever 121. When the beveled pinion 118 is shifted to the left, the beveled pinion will

be brought into mesh with the main beveled gear wheel 112 and into mesh with the beveled pinion 116 which is secured to the drive shaft 96. Then, motion will be transmitted from the spring 115 into the main beveled gear wheel 112 and from the main beveled gear wheel 112 into the beveled pinion 116 and the shaft 96, through the medium of the beveled pinion 118. When the shaft 96 is rotated in the manner hereinbefore set forth, rotary movement will be imparted to the blade holding head 130 by means of gear wheels 127 and 128.

At times, should the spring 116 be somewhat stiff, it may not be feasible to rotate the shaft 101 by means of the winding button 106. Under such circumstances, the stub-shaft 104 is threaded out of the end of the winding shaft 101 thus removing the winding button 106, and in the place of the winding button and the stub-shaft 104 there is employed a crank 135 shown in Fig. 5, the same coöperating with the squared end 102 of the winding shaft 101.

Having thus described the invention, what is claimed is:—

1. A spring motor comprising a casing; a drive shaft located in the casing; a winding shaft located in the casing; means for holding the winding shaft against rotation; a main gear wheel rotatable on the winding shaft; a spring forming an operative connection between the wheel and the winding shaft; movable means for locking the wheel; an auxiliary gear wheel fixed to the drive shaft; and a pinion movably supported on the casing, a portion of the locking means being operatively connected with the pinion to move the pinion into and out of mesh with the gear wheels.

2. A spring motor comprising a casing; a winding shaft located in the casing; a drive shaft located in the casing, the drive shaft and the winding shaft having their ends telescoped for relative rotation; means for holding the winding shaft against rotation; a main gear wheel rotatable on the winding shaft; a spring connecting the winding shaft and the main gear wheel; releasable means for locking the main gear wheel; an auxiliary gear wheel fixed to the drive shaft; and a pinion slidably supported on the casing, a portion of the locking means being operatively connected to move the pinion into and out of mesh with the gear wheels.

3. A spring motor embodying a casing; a drive shaft located in the casing; a winding shaft located in the casing; means for holding the winding shaft against rotation; a main gear wheel rotatable on the winding shaft; a spring connecting the winding shaft with the main gear wheels; an auxiliary gear wheel fixed to the drive shaft; a pinion slidably supported in the casing; a lever

fulcrumed on the casing; means carried by the lever for moving the pinion into and out of mesh with the gear wheels; and inter-engaging elements on the lever and the 5 main gear wheel for holding the latter against rotation.

In testimony that I claim the foregoing

as my own, I have hereto affixed my signature in the presence of two witnesses.

GUY L. BONHAM.
